INTERNAL-COMBUSTION ENGINE HAVING
MULTIPLE COMPRESSION AND EXPANSION

Albert Naccache, Beirut, Lebanon

Application August 10, 1946, Serial No. 689,703
In France December 12, 1945

5 Claims. (Cl. 60—15)

1

The present invention relates to gaseous fuel burning piston engines and more particularly to a means for increasing the efficiency of these engines by compression of the operating fluids and expansion of the inert exhaust gases in stages.

The objects of the invention are to provide improved means for achieving the five results listed below separately or in combination.

First.—Effecting compression of the feed fluids, whether gaseous mixture or air, by successive stages and in separate chambers.

Second.—Cooling the feed fluids after certain stages of their partial compression.

Third.—Effecting the expansion by successive stages and in separate chambers.

Fourth.—Effecting cooling of the power pistons which effect the final compression and at least the initial expansion, especially the cooling of these pistons by the circulation through their skirts either of feed fluids previously partially compressed and cooled, or else by circulation at high speed of air that has been compressed and cooled.

Fifth.—Scavenging of the inert gases of combustion from the engine by a compressed air blast into the combustion chamber at the end of the fourth stroke of the power piston in that chamber.

In order to achieve the objects outlined above, compression is carried out in separate chambers working in series, final compression being effected in the last chamber, that is, the chamber in which combustion occurs and which corresponds to the combustion chamber in a standard 4-stroke cycle engine.

On the other hand, expansion is carried out in two separate chambers operating in series, the initial expansion occurring in the combustion chamber, i. e., the same chamber, in which on the one hand the final compression occurs, on the other hand is the chamber in which initial expansion occurs.

The invention relies especially on the combination with one or more compressors of different receivers or reservoirs serving, as it were, as accumulators that allow, in the first place, the storing up of the fluids compressed and discharged by one or more compressors; in the second place, the cooling of these fluids; in the third place, the passage of these fluids through the airtight chamber formed by the inside of the pistons for cooling of the pistons; in the fourth place, the feed to the inlet valves of the engine as well as to the valves that control the delivery of the compressed air to the combustion chambers required

2

to scavenge waste gases; and, in the fifth place, for other useful purposes if required.

Connections and link-ups between the chambers of the various compressors and the control tanks or reservoirs, between the different tanks or parts of these tanks, and between these tanks and the compression chambers of the engine allow the meeting of the changing problems brought about by the various special cases concerned in their employment.

Other features of the improved engines of the present invention, all of which are assumed to be vertical for the purpose of illustration, are also brought out in the following description, taken by way of example, of the engines illustrated in the accompanying drawings, in which:

Fig. 1 is a fragmentary axial longitudinal sectional view of one form of engine constructed in accordance with the principles of the present invention;

Fig. 2 is a fragmentary side elevational view of the engine shown in Fig. 1;

Fig. 3 is a top plan view of the engine shown in Fig. 1;

Fig. 4 is an axial transverse sectional view of another form of engine embodying the principles of the present invention;

Fig. 5 is a fragmentary axial longitudinal section of the engine disclosed in Fig. 4;

Fig. 6 is a fragmentary side elevational view of the engine disclosed in Fig. 4;

Fig. 7 is a top plan view of the engine disclosed in Fig. 4; and

Fig. 8 is a sectional view taken on a substantially diametrical plane through the control valve 35 and the partition shown in Fig. 4.

Referring to Figs. 1 to 3, there is shown an internal combustion engine having an engine block 3 which has formed therein a pair of compressor cylinders 71 and 71a, two driving or power cylinders 9, 9a and a pressure reducing or expansion cylinder 72 into which exhaust gases are discharged from the two driving cylinders 9, 9a. All of these cylinders are arranged in line and the driving cylinders are of reduced diameter relative to the other cylinders.

Reciprocable within the drive cylinders 9 and 9a are hollow drive pistons 1 and 1a, and a hollow compression piston 1" is reciprocable in the expansion cylinder 72. These pistons 1, 1a, and 1" have ports 16, 16a, and 17, respectively, in their skirts which periodically during the reciprocation of the pistons register with ports 18, 18a, and 19 shown in Figure 3 in the side walls of the cylinders 9, 9a and 72. Preferably the power pistons 1 and 1a are four strokes or one cycle out of phase

relative to each other so that one piston is moving through its power stroke while the other is moving through its suction stroke.

This engine has a crank case 25, a fragment of which is shown in section in the lower portion of Fig. 1, and a crank shaft 24 driven by the drive pistons 1 and 1a and suitably supported in the crank case for rotation. The expansion piston 1" in the expansion cylinder 72 is operatively connected to and driven by the crank shaft, this piston being 180 degrees out of phase with respect to the drive pistons 1.

The means for feeding gaseous fluid such as a combustible fuel mixture or air to support combustion to the drive cylinders 9 and 9a includes means for passing this fluid through the pistons 1, 1" and 1a for the purpose of cooling these pistons. Referring to Fig. 3 it will be seen that a pair of control reservoirs or tanks 5 and 6 are secured by any suitable means on opposite sides of the engine block. Each of these tanks may be provided with suitable cooling means 12 (Fig. 2), such as a water cooling system, which may be of conventional construction. The cooling means in the tank 6 is similar to that in the tank 5, and is not separately illustrated. Thus, any fluid contained in or flowing through these tanks is cooled.

This fluid, which may be a gaseous fuel mixture or air as previously stated, depending on the type of engine, is drawn from any suitable conventional source into the compressor cylinder 71 through a channel 76 which has a suitable check valve 80 therein and is discharged through a duct 78 into the tank 5, a check valve 81 being provided in duct 78. From the tank 5 the fluid passes to the second cooling reservoir or tank 6, suitable ports and passageways 18, 18a, and 19 being provided to communicate the tank 5 with one side of the cylinders 9, 9a and 72. Other ports and passageways 23, 23a, and 24 connect the other side of the cylinders with the tank 6 so that the fluid in passing between these two tanks must necessarily pass through the ports in the cylinder walls and through the hollow pistons 1, 1a and 1" when the ports in the cylinders and pistons are brought into register by reciprocation of the pistons. Since the fluid is cooled in tank 5 it will absorb a large quantity of heat from the pistons, thereby cooling the latter.

Such heat as the fluid picks up in passing through the pistons 1, 1a and 1" is removed in cooling tank 6, the fluid remaining under pressure. From this tank the pressurized and cooled fluid flows through inlet conduits 13 and 13a (Fig. 3) and inlet valves 14 and 14a into the power cylinders 9 and 9a. These inlet valves are driven from the engine by suitable well known mechanism not shown and operate alternately so that one of the power pistons is moving through its power stroke while the other is moving through its intake stroke.

Exhaust gases from the power cylinders 9 and 9a are discharged into the expansion cylinder 72 through passageways 54 and 54a in the heads of the cylinders 9 and 72. Flow through these passageways is controlled by valves 53 and 53a (Fig. 3) driven from the engine by suitable mechanism not shown designed to open these valves alternately upon the suction strokes of the piston 1". Upon the compression or exhaust strokes of the piston 1" valves 53 and 53a are held closed and exhaust valves 55 (Fig. 1) open to establish communication between the expansion cylinder 72 and the atmosphere through ducts 13 (Fig. 3) for discharging the partially expanded exhaust gases in cylinder 72 to the atmosphere.

Assuming for the purpose of illustrating the operation of the engine that the power piston 1a, Fig. 1, is at the end of its compression stroke, the power piston 1 therefore is at the end of its exhaust stroke and the expansion piston 1" at the end of its suction stroke. At the moment the inlet valves 14 and 14a to the power cylinders 9 and 9a are both closed while the two inlet valves 53 and 53a to the expansion cylinder 72 and the exhaust valves 55 are also closed. Ignition of the combustible fuel mixture in the power cylinder 9a, which may be made to take place in a conventional manner not shown, and the consequent explosion or combustion of the gaseous fuel mixture causes the gases to expand and the power piston 1a to be driven through its power stroke. The power piston 1 being connected to the same crankshaft 24 as the power piston 1a is simultaneously driven by this connecting rod through its suction stroke, its inlet valve 14 opening to admit cooled fluid from the reservoir 6 through duct 13. During this time the expansion piston 1" being connected to the crank shaft is driven through an exhaust stroke, the valves 55 opening to allow discharge of the partially expanded exhaust gases from the cylinder 72 to the atmosphere while the valves 53 and 53a remain closed.

The power stroke of the piston 1a is followed by its exhaust stroke during which time the valve 53a associated with the cylinder 9a opens to admit exhaust gases from this power cylinder to the expansion cylinder 72 and the expansion piston 1" is moved through its intake stroke to allow the exhaust gases from the power cylinder 9a to expand partially. All other valves remain closed, and during this time the power piston 1a is moved through its compression stroke so that the parts are again in the position shown in Fig. 1.

Upon completion of the compression stroke of this piston the combustible mixture in the power cylinder 9 is ignited and the power piston 1 therein is driven through its power stroke, the valves associated with this cylinder remaining closed, while the inlet valve 14a to the power cylinder 9a opens to admit pressurized cooled fluid from the tank 6 to the power cylinder 9a. At this time both valves 53 and 53a which control communication through passageways 54 and 54a remain closed while valves 55 open so that exhaust gases are discharged from expansion cylinder 72 by the piston 1" which at the time is moving through its exhaust stroke.

In the last stroke in the cycle of operation of the power piston 1a all of the valves associated with its cylinder 9a remain closed so that the fluid previously introduced into this cylinder is compressed. At the same time the intake valve 14 associated with power cylinder 9 remains closed while the valve 53 associated with this cylinder opens so that exhaust gases in this power cylinder are discharged into the expansion cylinder 72, the piston 1" in this cylinder at this time moving through its suction stroke and the valves associated with this cylinder being closed.

This completes the description of one cycle of operation of each power cylinder, from which it will be seen that the expansion piston 1" completes two cycles for each cycle of the power pistons 1 and 1a.

To provide air compressed to the right pressure for scavenging the power cylinders 9, a sec-

ond compressor cylinder $71a$ is provided in which a piston $70a$ is reciprocable, this piston preferably being driven by the previously mentioned crank shaft 24 . It will be noted in Fig. 1 that the two compressor pistons 70 and $70a$ are 180 degrees out of phase relative to each other and displaced 90 degrees relative to the power pistons 1 and $1a$ and compressor piston $1''$. Upon the suction stroke of the piston $70a$, air is drawn through a passageway 75 into the compressor cylinder $71a$, a suitable inlet valve 82 being provided in this passageway. The compression chamber $71a$ is provided with the conventional inlet and exhaust valves $56a$ and $57a$, respectively. Air under pressure is discharged from the cylinder $71a$ upon the discharge stroke of the piston $70a$ in this cylinder past a suitable check valve 83 in a duct 79 (Fig. 3) and into a tank or reservoir 77 secured on one side of the engine block. Preferably this reservoir is cooled as is reservoir 5 by a conventional water cooling or other cooling system 12 .

A duct 84 connects the reservoir 77 to inlet valves 74 and $74a$ in the head of the driving cylinders 9 and $9a$. These valves may be of conventional construction not shown and are driven from the engine in timed relation to the movement of the power pistons 1 but so that they open for only a short interval just prior to the time that the exhaust strokes of the power pistons 1 and $1a$ end.

The volume of the reservoir 77 relative to the volume of the cylinder $71a$ supplying air thereto and the volume of the power cylinders 9 and $9a$ when the power pistons 1 and $1a$ approach the upper end of their stroke is such that the pressure of the air in reservoir 77 is always higher than the pressure of the inert gases in the upper end of either of the power cylinders 9 and $9a$ during the time the inlet valves 74 , $74a$ are open. Furthermore, the volume of air which may be delivered to either of the power cylinders is above the volume of the upper ends of these cylinders. Thus, the compressed air admitted through the inlet valves 74 and $74a$ scavenges the warm and inert exhaust gases from the upper ends of the power cylinders 9 and $9a$ causing these gases to be discharged past valves 53 and $53a$ into expansion cylinder 12 . At the same time the ends of the pistons 1 and $1a$ are cooled by this air.

It will thus be seen that there has been provided an improved engine in which compression of the operating fluids is performed in stages with the final compression occurring in the cylinder which forms the combustion or explosion chamber. Furthermore, these fluids are cooled between stages of compression so that they are cool when admitted to the combustion chamber and therefore may be compressed to a higher degree than if they were warm. Another advantage arising from the cooling of the operating fluid between the stages in its compression is the fact that this fluid may be used to cool the power pistons in its passage from the accumulator tank 5 to the tank 6 .

In accordance with another feature of the invention, expansion of the inert gases occurs by stages so that the full benefit of this expansion is received. Furthermore, means have been provided for assuring that all of the inert gases are removed from the combustion or explosion chamber at the end of the exhaust stroke of the power pistons therein so that a new charge of operating fluid is not contaminated by these gases or heat-

ed thereby, and the ends of the power pistons are cooled.

One of the disadvantages of the "in line" engine disclosed in Figs. 1 to 3 is the weakness of the connection between the power pistons 1 and $1a$ and their connecting rods. The relatively small size of these pistons limits the size of the connecting structure which may be provided. This difficulty is avoided in the modified engine disclosed in Figs. 4 to 8 by arranging the power and compressor pistons in tandem or axial alignment. The connecting rods are connected to the compressor pistons in these piston assemblies and since these compressor pistons are of larger size than the power pistons, room is present for a connection of the desired sturdiness.

In Figs. 4 to 8, the same or similar parts will be referred to by the same reference characters used to identify those parts in describing Figs. 1 to 3.

Referring to Figs. 4 and 5, it will be seen that the modified engine has a block 100 in which a plurality of axially aligned variable diameter first and second cylinders 102 , $102a$ and $102''$ and 101 , $101a$ and $101''$ respectively, are formed, separated by partitions 104 . Power pistons 1 and $1a$ are reciprocable in the cylinders 101 , $101a$ and $101''$ and are connected by rigid links 105 and $105a$, respectively, passing through partitions 104 to compressor pistons 103 , $103a$ which are reciprocable in the cylinders 102 , $102a$ from tubes 112 . The lowermost ends 120 , $120a$, $120''$ of the pistons 1 , $1a$ and $1''$ reciprocate in the lower end of cylinders 101 , $101a$, $101''$ and operate as compressors in these cylinders.

Air is admitted to the cylinder 102 from tubes 112 through ports 111 in the side walls thereof. Cylinders $102a$, $102''$ also have similar ports, such as ports $111a$, leading to tubes 112 . Discharge of air from these cylinders to an accumulator tank or reservoir 107 , which is divided by partitions 121 into a central compartment 123 and end compartments 124 , $124a$, is controlled by a rotary valve 22 (Figs. 4 and 8) mounted upon a shaft 11 driven from the engine by any suitable means not shown in timed relation to the movement of the pistons. This valve rotates in a water jacketed chamber and has passageways adapted upon rotation of the valve to be brought into communication with passageways in the partition members 104 communicating with the upper ends of the cylinders 102 , $102a$, $102''$ and with the lower ends of the cylinders 101 , $101a$, $101''$.

In general an engine having its power and compressor pistons arranged in tandem may be organized to operate in much the same manner as the engine previously described. The compressor pistons in the compressor cylinders compress the operative fluid in stages and this fluid is cooled at an intermediate stage or stages in an accumulator tank 5 . From this tank it flows through diametrically opposite ports 8 and $8a$ in the walls of the cylinders 101 , $101a$ and $101''$ to an accumulator tank 6 when diametrically opposite ports 7 and $7a$ in the power pistons 1 and $1a$ are brought into register with the ports 8 and $8a$ by reciprocation of the pistons 1 , $1a$ or it may be discharged directly to the atmosphere through ducts 113 and $113a$ as described herein-after. The cooled fluid flowing through the hollow power pistons 1 , $1a$ cools the same and the heat picked up by this fluid is extracted when it flows into the accumulator tank 6 . From the tank 6 the fluid may flow through conduits 13 and $13a$ to the chambers of inlet valves 14 and $14a$.

in the head of cylinder 101, 101a for admission to the working cylinder.

Thus in the engines illustrated in Figs. 4 to 7, the fluids required for the feed, for the cooling of the piston and for the scavenging of the waste gases are compressed by the compressors 103, 103a and 103'' and 120, 120a and 120'' to create a circulation of the various fluids through the accumulator tanks and through all the pistons 1 and 1a to the upper ends of the cylinders 101 and 101a which serve as combustion or explosion chambers.

For the collection and cooling of the fluids discharged by the compressors 103, 103a and 103'', a third accumulator tank 107 (Fig. 4) is provided and is cooled by liquid circulation or other suitable conventional means. As this tank is connected to the adjustment member or valve 22 of which it closes the ports, these last are cleared by straight ducts 110 (Fig. 4) or ducts 108 bent upwards allowing the fluids an airtight passage through the tank. A tubing 109 bent downwards allows ultimately certain of the compressors 120, 120a and 120'' to draw precompressed and cooled fluid for the combustion or explosion chambers from the bottom of accumulator tank 107. As explained previously, the tank 107 is divided into airtight compartments by vertical partitions 121, 121a and the compartment 123 may act as a scavenging air storage tank, storing up the compressed fluid required for the scavenging of the waste gases while compartments 124, 124a supply the compressors 120, 120a and 120''.

As previously explained, a discharge duct 113 (Fig. 4) in the accumulator tank 6 may if desired be arranged as an extension of the inter-communication ports 8 and 8a to allow the direct discharge into the atmosphere of the fluid which has been used to cool the power pistons 1 and 1a. In that case the tubing 13 and 13a connects the lower end of the accumulator tank 6 or its compartment 122 with the chambers of inlet valves 14 and 14a of the engine cylinders and conveys cooled fluid to the inlet valve chambers.

A tubing 114 may connect the lower end or the scavenging air chamber 123 of the accumulator tank 107, to the chambers of the scavenging air inlet valves 74 and 74a carried in the head of the engine cylinders 101 and 101a. The valves 74 and 74a are timed to be open for a short interval just prior to the time that the exhaust strokes of the power pistons 1 and 1a end. Tubing 115 interconnects the end compartments of the accumulator tank 5, which is divided by the partitions 117, to balance pressures in these compartments. Tubing 116 connects the distributor valve 22 with the central compartment of the accumulator tank 5.

While the principle of operation of the engine shown in Figs. 4 to 8 is similar to that of the engine shown in Figs. 1 to 3, a brief explanation follows, in which the compressors and explosion chambers are designated by letters, for purposes of clarity. The combustible mixture from the conduits 112 enters the compressor chambers E through the ports 111. The mixture is compressed and flows through the valve 22 into the end compartments 124 of the tank 107, from which it is withdrawn by the conduits 9 and distributing valve 22 into the compressor chambers C of the compressors 120. The combustible mixture is compressed for the second time and is expelled through the distributor valve 22, passageway 21, and conduit 106, into the cooling accumulator tank 5, from whence it flows through the pistons 1 and 1a to the accumulator tank 6

when ports 7 and 8 are aligned. The cooled combustible mixture from the tank 6 is admitted through the ducts 13 and 13a and inlet valves 14 and 14a to the cylinder chambers A. The burned and partially expanded gases are admitted to the expansion chamber B and then exhausted to the atmosphere.

Cooling of the expansion chamber piston 1'' is insured by air taken in through the ducts 110 and distributor valve 22 to the compressor chamber G. Compressed air flows through the valve 22 and the ducts 116 to the central compartment of the tank 5 and then through the aligned ports 7 and 8 in the piston 1'' and cylinder 72 to be exhausted through the duct 113.

Scavenging air is taken into the compressor chamber F through the port 111, is compressed, and is sent through the valve 22 to the central compartment 123 of the cooling tank 107. It is cooled and flows through the conduits 114 and valves 74 and 74a into the driving cylinder chambers A to scavenge the burned gases into the expansion chamber B.

Having thus described my invention, what I claim as new and useful and desire to secure by Letters Patent of the United States is:

1. In an internal combustion engine, a plurality of power cylinders, pistons in said power cylinders, an expansion cylinder adapted to receive exhaust gases from said power cylinders on the exhaust stroke of the pistons in said latter cylinders for further expanding said gases, a plurality of compression cylinders, a compression piston in each of said compression cylinders, a first cooling accumulator receiving fluid discharged from at least one of said compression cylinders, a second cooling accumulator, means for conveying fluid under pressure from said first accumulator to said second accumulator including ports through said power and expansion cylinders and pistons adapted to register for the flow of fluid therethrough for a portion only of the stroke of said pistons, a third cooling accumulator receiving air under pressure discharged from at least another of said compression cylinders, and means for establishing communication between said third accumulator and the inlet end of said power cylinders including means to admit cooled air to the cylinders for scavenging purposes and to cool said power pistons.

2. In a four cycle compound combustion engine, two piston operated fluid compressors, a cooling accumulator tank for receiving the fluid delivered by said compressors, two power cylinders, inlet valve means for said power cylinders, power pistons in said power cylinders, a relief cylinder for expanding the exhaust gases from said power cylinders, a piston in said relief cylinder, said pistons in said power and relief cylinders being hollow and said power and relief cylinders and pistons having apertures adapted to register during the reciprocation of said pistons, conduit forming means for connecting said compressor-fed fluid cooling tank with, the first of said power cylinders, said relief cylinder and the other of said power cylinders to establish a flow of cooled fluid through the said hollow pistons when said apertures register, outlet conduits adapted to recover the fluid heated in its passage through said pistons, cooling tanks into which said outlet conduits are adapted to discharge said heated fluid, and a pipe system for feeding cooled fluid to the inlet valve means for said power cylinders alternately to provide a constituent of an operating fluid for said power cylinders and to scavenge

the inert exhaust gases from the power cylinders.

3. In a compound combustion engine, two two-cycle piston operated fluid compressors, a cooling accumulator tank for receiving the fluid delivered by said compressors, two power cylinders, inlet valves for said power cylinders, four cycle pistons in said power cylinders, a relief cylinder for expanding the exhaust gases from said power cylinders, a two cycle piston in said relief cylinder, said pistons in said power and relief cylinders being hollow and having diametrically opposite apertures and said power and relief cylinders having apertures adapted to register with the apertures of the respective hollow pistons in said cylinders during the reciprocation of said pistons, conduit forming means for connecting said compressor-fed fluid cooling tank with, the first of said power cylinders, said relief cylinder and the other of said power cylinders to establish a flow of cooled fluid through said hollow pistons, outlet conduits adapted to recover the fluid heated in its passages through said cylinders and pistons, cooling tanks into which said outlet conduits are adapted to discharge said heated fluid, a pipe system for feeding the cooled fluid from said cooling tanks to the inlet valves of said power cylinders, a third compressor, an auxiliary tank adapted to receive the air delivered by said third compressor together with means for utilizing this air for scavenging the burned gases from said power cylinders.

4. In an internal combustion engine, a plurality of power cylinders, pistons in said power cylinders, an expansion cylinder adapted to receive exhaust gases from said power cylinders on the exhaust stroke of the pistons in said latter cylinders for further expanding said gases, a plurality of compression cylinders, a compression piston in each of said compression cylinders, said power cylinders each being arranged in tandem with compression cylinders, a first accumulator receiving fluid discharged from one or more compression cylinders, a second accumulator, means for conveying fluid under pressure from said first accumulator to said second accumulator including ports through said power and expansion cylinders and pistons in register for the flow of fluid therethrough for a portion only of the stroke of

said pistons, a third accumulator receiving air under pressure discharged from one or more compression cylinders, means for establishing communication between said third accumulator and the inlet end of said power cylinders including means to admit air to the power cylinders for scavenging purposes, a common crank shaft for said pistons, and means for establishing communication between said first and third accumulators and predetermined compression cylinders including a distributing valve operated by said engine, said valve also controlling the flow of fluid to and from the compression cylinders supplying said first accumulator.

5. An internal combustion engine as defined in claim 4, wherein each of said power cylinders is arranged in tandem with first and second compression cylinders and wherein interconnected pistons are provided in said cylinders, including 15 a double acting piston having one side constituting a power piston and its opposite side constituting a first compression piston, and wherein a second compression piston is provided connected to said double acting piston and to said crank shaft.
